APPARATUS FOR CONVERTING ELECTRICAL FREQUENCY VARIATIONS INTO AMPLITUDE VARIATIONS

Carmen L. Cuccia, Princeton, N. J., assignor to Radio Corporation of America, a corporation of Delaware

Application May 28, 1949, Serial No. 95,976

8 Claims. (Cl. 250—20)

1

My invention relates to a method and apparatus for converting electrical frequency variations into amplitude variations, particularly at ultra high frequencies.

A paper entitled "Frequency Modulation and Control by Electron Beams," by Lloyd P. Smith and Carl I. Shulman, Proc. of I. R. E., July 1947, pages 644-57, describes a method of frequency modulating a resonant electrical system by use of a spiral electron beam. A beam of electrons is projected at uniform velocity along a path lying between and parallel to two parallel plates, which are connected to a source of oscillating voltage of frequency f to establish an oscillating electric field extending between the plates. A constant magnetic field is provided parallel to the beam. Due to the crossed electric and magnetic fields the electrons revolve about the beam axis in spiral paths. It is shown that when the magnetic field strength H is adjusted so that the cyclotron angular frequency, or angular velocity of the electrons about the axis,

$$\omega_0 = \frac{He}{m}$$

is equal to the angular frequency $\omega = 2\pi f$ radians per second of the oscillating voltage source, where e and m are the charge and mass, respectively, of an electron, the electron beam functions as a purely resistive load on the system. When the magnetic field is so adjusted that:

$$\theta = (\omega_0 - \omega) \tau = \pm 2\pi \text{ (radians)} \quad (1)$$

where τ is the transit time of the electrons between the plates in seconds, the beam is purely reactive, and the net absorption of energy from the input system by the beam is zero. For values of $\theta = (\omega_0 - \omega) \tau$ between 0 and $\pm 2\pi$, the beam exhibits both resistive and reactive properties.

In accordance with my invention, I utilize the principles set forth in the aforesaid paper in an electron coupler device, which may be similar to the devices described in my co-pending application entitled "Microwave Coupling System and Apparatus," Serial No. 754,756, filed June 14, 1947, now Patent No. 2,542,797, dated February 20, 1951, and assigned to the same assignee as the instant application. The electron coupler comprises essentially an evacuated envelope containing a first pair of parallel deflecting plates, a second pair of parallel plates either aligned with or rotated 90° with respect to the first pair, means connected to the first pair of plates for establishing a high frequency electric field therebetween, means for supplying and directing an electron beam successively through the spaces be-

2

tween the plates to a collector, means for subjecting the electron beam to a constant magnetic field parallel to the beam path, and means connected to the second pair of plates for extracting electrical energy from the coupler. Briefly, my invention comprises connecting the first pair of parallel plates of the electron coupler to a source of variable frequency microwave energy, such as a frequency-modulated signal voltage, adjusting the transit time τ of the electrons across the plates by adjusting the beam accelerating voltage so that the total frequency swing $2\Delta\omega$ of the signal multiplied by the transit time τ equals 2π radians, and adjusting the strength of the magnetic field so that He/m equals the maximum angular frequency of the signal. Under these conditions, when the instantaneous signal frequency ω is a maximum, that is, when the signal modulation is maximum positive, θ is zero, and hence, the net absorption of energy by the beam from the input system is a maximum and the energy given up by the beam to the output system is also a maximum. When the instantaneous signal frequency ω is the minimum frequency, that is, when the modulation is maximum negative, θ is 2π , and hence, the beam absorbs no energy from the input system and, therefore, delivers no energy to the output system. Thus, the variation of the instantaneous frequency of the input signal from its maximum to its minimum value results in 100% amplitude modulation in the output system. The device serves as a converter to change frequency modulation to amplitude modulation.

The object of the present invention is, therefore, to provide a novel method of converting frequency variations to amplitude variations. More specifically, the object is to utilize spiral beam devices such as disclosed in my co-pending application referred to above as detectors for frequency-modulated signals.

Another object is to provide means for minimizing distortion in the output due to the frequency-changing properties of the beam during portions of the modulation cycle. A further object is to provide a mixer for a frequency modulation superheterodyne circuit.

These and other objects and advantages of my invention will be evident from the following detailed description.

The novel features which I believe to be characteristic of my invention will be set forth with particularity in the appended claims, but the invention itself will best be understood by reference to the following description taken in connection with the accompanying drawings, in

which Figure 1 is an axial sectional view of an electron discharge device with which my invention may be practised; Figure 2 is a transverse section view taken on the line 2—2 of Figure 1; Figure 3 is a schematic view of the device shown in Figure 1 showing a different mode of operation; Figure 4 is a graph used in describing my invention; Figure 5 is a schematic diagram of a circuit embodying my invention; and Figure 6 is a schematic circuit diagram illustrating a modification of my invention in which the electron coupler is used as a mixer.

Referring to Figures 1 and 2, the device shown comprises a pair of axially aligned, spaced cavity resonators 1 and 3 of cylindrical cross section. The resonator 1 comprises an outer cylindrical wall 5 and apertured end walls 7 and 9. The resonator 3 comprises an apertured end wall 11 and solid end wall 13. Two spaced parallel deflecting plates 15 are mounted by means of conducting stubs 17 within resonator 1 as shown. Similarly, two spaced parallel output plates 19 positioned at right angles to plates 15 are mounted on conducting stubs 21 within resonator 3. The space between the resonators 1 and 3 is closed by suitable insulating sealing means 23. In order to provide means for exciting the input resonator 1, a coupling loop 25 is mounted within the resonator as shown, the loop 25 forming a continuation of the center conductor of an input coaxial transmission line 27. A similar output coupling loop 25' and line 27' are provided in the output resonator 3.

An electron gun structure, including an indirectly-heated cathode 29, an apertured accelerating and beam-forming electrode 31 and an apertured beam-forming electrode 33, is suitably mounted at the entrance to the resonator 1 in position to project an electron beam coaxially through the two resonators and between the plates 15 and 19 toward the wall 13, which serves as a collector.

Suitable means, such as an electromagnet 35 surrounding the two resonators, is provided for establishing a constant magnetic field extending along the beam axis. The cathode 29 is connected to the negative terminal and the accelerating electrodes 31 and 33 and resonators 1 and 3 are connected to an adjustable relatively high positive point on a direct-current voltage source, such as a battery 37, in order to give the electron beam the desired axial velocity.

In operation, the input line 27 is connected to a source of microwave energy which in my invention is a variable frequency generator signal. The microwave current in the coupling loop 25 induces an electromagnetic field within the resonator which establishes an oscillating electric field between the deflection plates 15. Electrons entering this field along the central axis are deflected toward the plate having the higher instantaneous positive potential. However, due to the component of electron motion normal to the axial magnetic field each electron is deflected by the magnetic field and caused to follow a curved path. As each electron absorbs energy from the fields its velocity tangent to the curved path increases which causes the radius of curvature to increase. Hence, electron follows a spiral path of increasing radius, which at any instant is determined by a condition of equilibrium between the centrifugal force due to the instantaneous spiral energy of the electron, the deflecting force due to the constant magnetic field and the deflecting force due to the instantaneous electric field.

If the strength H of the magnetic field and the angular frequency ω of the deflecting electric field are so related that $He/m = \omega$, the electrons of the beam will continuously extract energy from the electric field, and hence, the radius of the spiral path will increase uniformly as the electron traverses the input field region. All the electrons in the beam have the same angular velocity ω_0 , and therefore, at any instant they lie along a straight line, as indicated in Figure 1 by the dotted lines 39. During a complete cycle of the input electric field the line beam 39 swings at angular velocity ω_0 about the tube axis and generates a conical surface, as indicated by the dash line 41 in Figures 1 and 2. This portion of the beam is sometimes termed a cone-directrix beam. In their travel through the intermediate space between the deflection plates 15 and output plates 19, the electrons experience no transverse electric field, and hence, the radius of the spiral path is unchanged and the beam is a cylinder-directrix line beam. Entering the space between the output plates 19 the spiraling electrons induce an oscillating voltage on the plates and thus give up energy to the output resonator 3. The angular velocity of the individual electrons and the beam is constant throughout the intermediate and output regions and is equal to $\omega_0 - He/m$. Hence, energy is continuously extracted from the beam by the output resonator at the angular frequency $\omega = \omega_0$, causing the tangential velocity of the electrons to decrease with the result that the beam is a cone-directrix beam of decreasing radius. For best results, the two resonators should be constructed to be resonant at ω_0 .

On page 647 of the above-mentioned paper by Smith and Shulman, it was shown that when an electron beam is projected parallel to a constant magnetic field and through the space between a pair of parallel plates connected to a source of oscillating voltage of frequency ω , the electronic conductance introduced by the beam is

$$G_e(\theta) = \frac{L^2}{4d^2} \frac{|I_0|}{V_0} \frac{1 - \cos \theta}{\theta^2} \quad (2)$$

where L is the axial length of the plates, d is the distance between the plates, $|I_0|$ is the absolute value of the beam current, V_0 is the beam accelerating voltage, and $\theta = (\omega_0 - \omega)\tau$. It can be seen from Equation 2 that $G_e(\theta)$, which is a measure of the net power absorbed by the beam from the electric field, is a maximum when $\theta = 0$, and zero when $\theta = 2\pi$. When $\theta = 0$

$$G_e(\theta) = \frac{L^2}{4d^2} \frac{I_0}{V_0} \frac{1}{2} \quad (3)$$

In Figure 1, the dotted lines 39 and 39' illustrate the straight line nature of the beams in the input and output regions when $\theta = 0$, that is, when $\omega = \omega_0$. Theoretically, if the input and output electric field regions are similar, all of the energy absorbed by the beam in the input region will be given up in the output region, so that the beam collected at 13 will have no residual spiral energy.

In Figure 3 is shown schematically the nature of the beam when $\theta = \pm 2\pi$. From Equation 2 it can be seen that the electronic conductance of the beam is zero. All of the spiral energy absorbed by the beam in the input cavity resonator is given back to that cavity resonator. The beam then enters the output cavity with no spiral energy, and hence, the output power is zero. The beam in the input cavity is not a straight line cone-directrix as in Figure 1. If an electron begins spiralling in phase with the ap-

plied electric field ω at time $t=0$ when it first enters the input region, at a time t its phase angle will be $\omega_0 t$ and the phase angle of the electric field will be ωt . Thus, the difference in phase between the electron and the electric field at the time τ when the electron leaves the input region will be $\theta = \omega_0 \tau - \omega \tau$ radians. When $\theta = +2\pi$ this phase difference is one cycle, and the electron executes $n+1$ revolutions about the axis during n cycles of the applied electric field. Hence, at any instant the part of the beam within the input region has the form of a single turn helix or spiral of increasing radius during the first half and decreasing radius during the second half, as indicated at 43 in Fig. 3. The beam itself rotates about the axis at the angular velocity ω of the input electric field, generating a curved surface of revolution 45.

If the frequencies of the signal used to excite the input resonator 1 are suitably related to the magnetic field strength and electron transit time, the device shown in Figures 1-3 can be utilized to convert frequency variations in the signal to amplitude variations of constant carrier frequency in the output circuit. In Figure 4, curve A represents the variation in angular frequency ω of a signal having a carrier frequency ω_0 and a sine wave frequency modulation of amplitude $\pm \Delta\omega$ as a function of the phase angle ϕ_m of the modulation. C indicates one modulation cycle. The maximum frequency is $\omega_1 = \omega_0 + \Delta\omega$ and the minimum frequency is $\omega_2 = \omega_0 - \Delta\omega$. Curve B represents the positive half of the envelope of the microwave voltage induced by the revolving beam in the output cavity. Suppose that ω_1 is made equal to $\omega_0 = He/m$ of the magnetic field used. When the modulation is a maximum, at point a on curve A, that is, when $\omega = \omega_1 = \omega_0$, $\theta = 0$ and the electronic conductance and the output power will be greatest, as indicated at point b on curve B. If the total frequency swing $2\Delta\omega$ of the signal is such that $(\omega_1 - \omega_0)\tau = 2\pi$, the value of $\theta = (\omega_1 - \omega_0)\tau$ will be 2π when the modulation is a minimum, at point a' on curve A, and the electronic conductance and output power will be zero, as indicated at point b' on curve B. When the modulation is zero, at point a'' on curve A, $\theta = \pi$, and

$$G_e(\pi) = \frac{L^2}{4d^2} \frac{|I_0|}{V_0} \frac{2}{\pi^2} \quad (4)$$

Comparing Equations 3 and 4, it is seen that $G_e(\pi)$ is approximately four tenths of $G_e(0)$, as indicated by point b'' on curve B. Although the wave form of the output curve B is not exactly the same as that of the input curve A, it is very similar thereto, and the variation is so slight that little distortion in the signal will be produced during the conversion of a frequency modulated signal to an amplitude modulated output. The beam revolves around the axis in the output resonator at the frequency f of the signal. Hence, the output voltage varies in frequency and amplitude in accordance with the signal modulation. However, the frequency variation can be ignored. The output voltage from the coupler can be fed into any suitable audio or video frequency detector to recover the modulation intelligence. If desired, the signal can be re-broadcast, after conversion from FM to AM, as an amplitude modulated signal.

In practice, the conditions set forth in the preceding paragraph may be obtained by first adjusting the beam voltage to adjust the transit time τ so that $2\Delta\omega\tau = 2\pi$, and then adjusting the

magnetic field strength, by adjusting the current source 35', to make

$$\omega_c + \Delta\omega = \omega_0 = \frac{He}{m}$$

For example, if the input carrier frequency f_0 is 4000 megacycles, the deflecting plate length L is 10 cm., and Δf is 30 megacycles, τ will be about 1.68×10^{-8} second, the beam voltage will be about 100 volts, H will be about 1430 gauss, and the number of cycles n of the input carrier frequency during the time τ will be about 67.

In Figure 5 I have shown a circuit, for use with an electron coupler such as that of Figures 1-4, which includes means for minimizing distortion due to changing impedance of the input cavity of the coupler during a frequency modulation cycle. As indicated schematically, a frequency-modulated signal is fed into a variable-gain amplifier which is inductively coupled to the input circuit D of the coupler. If the beam current is low and the shunt resistance R_s is made less than the resistance R_e of the electron beam device, the frequency change will be in such a direction that the increase in the reflected reactance from the coupler may compensate for the shift in frequency off the resonant frequency of circuit D.

In some cases it may be advantageous to utilize the resonance characteristics of the output cavity to achieve FM-AM conversion rather than work strictly from $\theta = 0$ to $\theta = 2\pi$, since the output of the coupler may go to zero before frequency modulation swing reaches an ω corresponding to $\theta = 2\pi$. This operation may be used to reduce frequency distortion during a modulation cycle.

The electron coupler may also be used as a mixer in superheterodyne circuits, as shown schematically in Figure 6. In this figure the coupler structure may be the same as in Figs. 1-4. A frequency-modulated signal f is used to excite the input resonator 1 in the same manner as described in connection with Figs. 1-4. A local oscillator is connected between cathode 29 and control grid 31 to pre-modulate the electron beam current density before entering the input resonator at a frequency f_3 suitably related to the carrier frequency f_c of the FM signal. The modulation of the beam current density would produce amplitude modulation of the output voltage at the frequency of the oscillator if the amplitude and frequency of the microwave energy applied to the input resonator were constant. However, the use of a frequency modulated signal of frequency f in the input resonator in combination with a local oscillator voltage of frequency f_3 for pre-modulating the beam will produce amplitude modulated output voltages of frequencies f , f_3 , $f + f_3$, and $f - f_3$ (or $f_3 - f$, if $f_3 > f$). The apertured electrode 31 of Fig. 1 may be used as the control grid, with a suitable negative bias potential applied thereto.

While I have indicated the preferred embodiments of my invention of which I now am aware and have illustrated only one specific structural embodiment it will be apparent that my invention is by no means limited to the exact embodiments or structure disclosed or the uses indicated, but that many variations may be made in the particular structure used and the purpose for which it is employed without departing from the scope of the invention as set forth in the appended claims. For example, although the invention is best suited for use with cavity resonators at microwave or ultra high frequencies,

the resonators may be replaced by conventional tuned circuits at lower frequencies. Various kinds of beam-forming and focussing electrodes may be used instead of or in addition to those disclosed. The magnetic field may be adjusted to correspond to some frequency other than the maximum frequency of the signal. The electron beam may be collected by a separate collector held at a positive potential somewhat below that of the accelerating electrodes and resonators.

The resonators at microwaves may be in the form of half-wave length coaxial line resonators, shorted at either end, appropriate lengths of short-circuited rectangular wave guide excited to yield a proper transverse field, or even cavity resonators of the type shown in Fig. 3 or Fig. 14 (magnetron cavities) in my above-mentioned co-pending application.

I claim:

1. A system comprising: an electron discharge device including means for supplying and directing a beam of electrons along a predetermined beam path, a pair of deflecting electrodes adjacent said means and disposed on opposite sides of said path, a pair of inductive output electrodes spaced from said first pair and disposed on opposite sides of said path, and means for collecting said beam of electrons; a cavity resonator coupled to said deflecting electrodes; a source of variable frequency energy coupled to said resonator to establish a variable frequency electric field between said deflecting electrodes; means for establishing a constant magnetic field parallel to said path; means for adjusting the strength of said magnetic field; and an output cavity resonator coupled to said pair of inductive output electrodes.

2. A system according to claim 1, further comprising a control electrode in said path between said electron supplying means and said deflecting electrodes, and an oscillator coupled to said electron supplying means and said control electrode, for modulating said beam.

3. A system according to claim 1, further comprising a resistor connected in parallel with said deflecting plates and having a resistance somewhat lower than the beam resistance of said electron discharge device.

4. An electrical system comprising: means for generating an electron beam along a predetermined initial path; means for establishing a constant magnetic field substantially parallel with said path; means, including first electrode means adjacent said path and a source of variable frequency voltage coupled to said electrode means, for establishing an alternating electric field of variable frequency transverse to said path and said magnetic field, for causing the electrons of said beam to traverse spiral paths having radii dependent upon the net energy absorbed by said electrons from said electric field; and second electrode means, adjacent and spaced laterally from said spiral paths and separate from said first

electrode means, for inductively extracting spiral energy from said beam.

5. A system according to claim 4, wherein the strength of said magnetic field is adjusted so that

$$\frac{He}{m}$$

is equal to a predetermined value of said variable frequency, where H is the magnetic field strength and e and m are the charge and mass, respectively, of an electron.

6. A system according to claim 5, wherein said variable frequency voltage is a frequency modulated signal,

$$\frac{He}{m}$$

is made substantially equal to the maximum frequency of said signal, and the electron transit time through said electric field is adjusted to a value substantially equal to 2π divided by the total angular frequency swing of said signal.

7. A system according to claim 6, further comprising means for pre-modulating said beam at a predetermined frequency prior to the passage thereof through said electric field.

8. An electrical system comprising: means for generating an electron beam along a predetermined initial path; means for establishing a constant magnetic field substantially parallel with said path; means, including a pair of deflecting electrodes adjacent said first-named means and disposed on opposite sides of said path and a source of variable frequency voltage coupled to said electrodes, for establishing an alternating electric field of variable frequency transverse to said path and said magnetic field, for causing the electrons of said beam to traverse spiral paths having radii dependent upon the net energy absorbed by said electrons from said electric field; and means, including a pair of inductive output electrodes spaced from said first pair and disposed on opposite sides of said path, for inductively extracting spiral energy from said beam.
